UNITED STATES PATENT OFFICE.

GUSTAF A. SELVIG, OF MINNEAPOLIS, MINNESOTA.

BUTTER-CUTTER.

1,288,702.

Specification of Letters Patent. Patented Dec. 24, 1918.

Application filed March 6, 1918. Serial No. 220,742.

To all whom it may concern:

Be it known that I, GUSTAF A. SELVIG, a citizen of the United States, resident of Minneapolis, county of Hennepin, State of Minnesota, have invented certain new and useful Improvements in Butter-Cutters, of which the following is a specification.

The object of my invention is to provide a butter cutter by means of which a block or brick of butter can be easily and quickly cut into a series of small blocks or squares of suitable size for table use.

A further object is to provide a butter cutter in which all the squares cut at one operation of the device will be of the same size and without any waste.

A further object is to provide a cutter of compact, simple construction and one which can be easily and quickly manipulated.

20 The invention consists generally in various constructions and combinations, all as hereinafter described and particularly pointed out in the claims.

In the accompanying drawings forming 25 part of this specification,

Figure 1 is a plan view of a butter cutting device embodying my invention,

Fig. 2 is a longitudinal sectional view of the same,

30 Fig. 3 is a side elevation, showing the manner of cutting a block of butter,

Fig. 4 is an end view,

Fig. 5 is a detail sectional view of the butter cutting frame, showing the preferred 35 manner of mounting a cutting wire therein,

Fig. 6 is a similar view, illustrating the mounting of the wire on the opposite side of the frame.

In the drawing, 2 represents a suitable 40 base on which the butter cutting apparatus is mounted. At one end of this base I prefer to provide an upright standard 3 forming a guide for a hub 4. The standard is provided with a longitudinal slot 5 to receive 45 a screw 6 which, with said slot, guides the hub in its vertical movement and prevents it from turning on the standard. Near the top of the standard I prefer to provide an annular groove 7 which, when the screw registers therewith, will allow the hub to be 50 revolved on the standard.

A frame 8 is mounted on said hub and projects horizontally therefrom and is preferably rectangular in form and carries the 55 cross wires for cutting the vertical slits

through the block of butter. There may be any desired number of these wires, according to the length of the frame and the desired size of the butter squares.

The side rails of the frame are provided in their upper and under surfaces with transverse slits 9 and 10, the former being formed in the under surface of one rail and the latter in the upper surface of the other rail and the slits of one group are preferably nearer together than those of the other group so that the thickness of the butter squares may be varied according to the size desired for the table. Each rail has a recess 11 in its outer face, with a notch 12 60 therein to receive a head 13 on the end of the cutting wire 14, while the other end of the wire extends through a hole 15 in the opposite rail and is attached to a plug 16 65 which is tapped into the under side of the rail and is adapted to be moved back and forth to tighten or loosen the wire. The opposite side of the rails is equipped with a similar means for fastening the wires, which may be easily and quickly transferred from 70 one side of the frame to the other, the frame being reversible on the guiding standard for the positioning of either group of cutting wires on the top of the frame.

The end rail of the frame adjacent the hub is also provided with notches 17 in its upper and under surfaces to receive the head of a cutting wire 18 that is secured in the opposite end rail of the frame by a plug 16^a 75 that is tapped into the upper and under surfaces of said rail, as may be desired, according to the position of the cross wires of the frame. This longitudinal wire 18 serves to cut the block of butter vertically and lengthwise thereof and co-operates with 80 the cross wires to form the desired size of squares.

19 is a slide, mounted to move back and forth on the frame and having depending arms 20 provided with slits 21 in which the ends of the cross wire 22 are secured. This wire 22 has the function of dividing the block horizontally and its movement forms the first step in the cutting operation, the block being divided thereby into an upper and lower section ready for the final division into the small squares for table use when the frame is moved downwardly on its guiding standard.

Upon the base 2 I arrange a stationary 110

plate 23 secured to the base at one end by suitable means, such as screws 24 and having a supporting standard 25 at the opposite end of the base. This plate is reversible on the base, the standard 25 having a pin 26 at its upper end fitting within a socket 27 in the plate and removable therefrom. Each surface of the plate is divided by transverse grooves 28 and a longitudinal groove 29 into a series of rectangular supporting surfaces for the butter squares, the grooves between these surfaces allowing the cutting wires to pass down entirely through the butter block and the group of grooves in the opposite surfaces of the plate are differently spaced to correspond to the variation in distance between the cutting wires in the upper and under surfaces of the frame, so that whenever it is desired to vary the size of the butter squares and the cutting wires are moved in the frame for that purpose, the base supporting the block of butter will be inverted so that the grooves in the upper surface will be positioned to receive the cutting wires when they have been forced down through the block of butter.

At the inner end of the plate 23 I prefer to provide an upright plate 30 against which the end of the block of butter is seated, a vertical slit 31 being provided in this plate in which the longitudinal cutting wire of the frame is vertically movable.

The device may, of course, be made in various sizes and the position of the wires changed according to the desired size of the butter squares.

I claim as my invention:

1. A butter cutter comprising a base, a plate mounted for inversion thereon and adapted to support a block of butter, and having a series of differently spaced slots in its upper and under surfaces, a vertically movable frame having cutting wires mounted therein, said wires being mounted for adjustment in said frame to vary the distance between them to adapt said frame for the face of the supporting plate that is uppermost to register said wires with the slots in said frame.

2. A butter cutter comprising a base, a butter supporting plate thereon, a vertically movable frame comprising side and end rails having recesses and slots in their upper and under surfaces, those in one surface be-

ing spaced apart a greater distance than those in the other surface, and butter cutting wires mounted in said recesses and slots for adjustment from one surface of said frame to the other surface thereof.

3. In a butter cutter, a vertically movable frame having side and end rails, one of said end rails having notches in its upper and under surfaces to receive one end of a butter cutting wire seated therein, the other end rail having sockets in its upper and under surfaces and a plug tapped into said sockets and engaging the other end of the butter cutting wire for putting it under tension between the ends of said frame, said frame being mounted for inversion to position the butter cutting wire at the top of said frame.

4. A butter cutter comprising a base having a support whereon the block of butter to be cut is placed, and an upright standard, of a frame vertically slidable on said standard and guided thereby, said frame comprising side and end rails, wires mounted in said side and end rails for dividing the butter transversely and longitudinally, a slide carried by said frame, and a wire supported by said slide for dividing the butter horizontally into an upper and a lower section.

5. A butter cutter comprising a base, a butter supporting plate thereon, a vertically slidable frame having side and end rails provided in their upper and under surfaces with groups of differently spaced recesses, and wires having means for mounting them in parallel relation in either of said groups of recesses for varying the thickness of the squares of butter, and said frame being reversible on its support, for the purpose specified.

6. A butter cutter comprising a base having a support for a block of butter thereon, an upright standard, a frame vertically slidable and reversible on said standard, a series of wires mounted in parallel relation in said frame, said frame having means for mounting said wires with different widths or spaces between them in the upper and under surfaces of said frame, for the purpose specified.

In witness whereof I have hereunto set my hand this 16th day of February, 1918.

GUSTAF A. SELVIG.
